United States Patent Office

Des. 181,569
Patented Nov. 26, 1957

181,569

TOY FOX

Robert Zeidman, Mamaroneck, N. Y., assignor to Mail Pouch Tobacco Co., Wheeling, W. Va., a corporation of Delaware

Application March 19, 1957, Serial No. 45,330

Term of patent 3½ years

(Cl. D34—2)

Fig. 1.

Fig. 2.

Fig. 3.

I claim:

The ornamental design of a toy fox, substantially as shown.
